UNITED STATES PATENT OFFICE.

JOSEPH ARANYI, OF WALLINGFORD, CONNECTICUT, ASSIGNOR TO INTERNATIONAL SILVER CO., OF MERIDEN, CONNECTICUT, A CORPORATION OF NEW JERSEY.

DESIGN FOR A HANDLE FOR SPOONS, FORKS, OR SIMILAR ARTICLES.

45,053.

Specification for Design.

Patented Dec. 23, 1913.

Application filed October 13, 1913. Serial No. 795,020. Term of patent 7 years.

To all whom it may concern:

Be it known that I, JOSEPH ARANYI, a citizen of the United States, residing at Wallingford, in the county of New Haven and State of Connecticut, have invented a new, original, and ornamental Design for a Handle for a Spoon, Fork, or Similar Article; and I do hereby declare the accompanying drawings to be a full, clear, and exact illustration of the same, and which said drawings constitute part of this application, and represent, in—

I claim:

The ornamental design for a handle for a spoon, fork or similar article, as shown.

JOSEPH ARANYI,

Witnesses:

CLIFTON D. ALLEN,
JOHN A. MARTIN.
